WEATHER INDICATING INSTRUMENT

Walter I. Bieger, St. Anthony Village, Minn., assignor to Honeywell Inc., Minneapolis, Minn., a corporation of Delaware

Filed Aug. 23, 1967, Ser. No. 8,367

Term of patent 14 years

(Cl. D52—7)

FIG. 1

FIG. 2

FIG. 4

FIG. 3

FIG. 5

FIG. 6

FIGURE 1 is a front elevational view of a weather indicating instrument disclosing the new design;

FIGURE 2 is an elevational view taken from the right side of the instrument, the left side being substantially a mirror image thereof;

FIGURE 3 is an end view taken from the bottom of the instrument, the top end being substantially a mirror image thereof;

FIGURE 4 is a longitudinal cross-sectional view taken along line 4—4 in FIGURE 1;

FIGURE 5 is a transverse cross-sectional view taken generally along line 5—5 in FIGURE 1;

FIGURE 6 is a transverse cross-sectional view taken generally along line 6—6 in FIGURE 1.

The dominant features of the design reside in the portions shown in full lines.

I claim:

The ornamental design for a weather indicating instrument, substantially as shown and described.
